Primary Examiner — Jennifer Rivard

(74) Attorney, Agent, or Firm — Greer, Burns & Crain, Ltd.

(57) **CLAIM**

The ornamental design for a hair clipper housing, as shown and described.

DESCRIPTION

FIG. 1 is a top perspective view of the present hair clipper housing;

FIG. 2 is a front view of same;

FIG. 3 is a rear view of the hair clipper housing of FIG. 1;

FIG. 4 is a left side view of same;

FIG. 5 is a right side view of the hair clipper housing of FIG. 1;

FIG. 6 is a top view of same; and,

FIG. 7 is a bottom view of the hair clipper housing of FIG. 1.

The broken line disclosures of the clipper blade and adjustment handle illustrate the environment. The remaining broken lines illustrate portions of the hair clipper housing. None of the broken lines forms part of the claimed design.

1 Claim, 6 Drawing Sheets
